Patented Jan. 31, 1922.

FIG. 1

FIG. 2

INVENTOR

PHILIP J. WERBER
by Arthur C. Eckert, Attorney.

UNITED STATES PATENT OFFICE.

PHILIP J. WERBER, OF ST. LOUIS, MISSOURI.

TELEPHONE ATTACHMENT.

1,404,817.

Specification of Letters Patent.

Patented Jan. 31, 1922.

Application filed February 28, 1921. Serial No. 448,706.

To all whom it may concern:

Be it known that PHILIP J. WERBER, a citizen of the United States of America, residing at St. Louis and State of Missouri, has invented certain new and useful Improvements in Telephone Attachments, of which the following is a specification.

My invention relates to telephone attachments which have for their purpose the construction of a telephone receiver and transmitter which can be effectively used when the operator is surrounded with disturbing noises, or when he does not desire to have the party to whom he is speaking hear conversation that is taking place in the immediate vicinity of the operator.

In a foundry or other noisy place it is almost impossible to effectively use a telephone without placing the hand over the transmitter mouthpiece in order to prevent the noise from without entering the mouthpiece. Customarily the hand is placed over the mouthpiece. My purpose is to effectively and positively bring about this result mechanically, i. e., by damping the vibration of the transmitter. With this and other objects in view my invention has relation to certain novel features of construction and arrangements of parts as will be hereinafter more fully described and pointed out in the drawings in which—

Fig. 1. is a fragmental sectional elevation of a conventional telephone transmitter and mouthpiece with my device attached.

Fig. 2. is an enlarged sectional elevation of my device removed from a transmitter.

Numeral 3 indicates a conventional transmitter casing to which is attached the con-

ventional mouthpiece 4 and in which is located the vibrating transmitter diaphragm 5. On the casing 3 at 6 my device is placed. It consists of a rod 7 passing through a hole in the casing 3 and on the inner end of which is positioned the button 8. The washer 9 is then placed over the rod 7 externally to the casing 3; the coil spring 10 is then placed over the rod 7 external to the washer 9. Numeral 11 indicates a cup with a hole in its closed end. Rod 7 passes through this hole and the cup 11 is secured to the rod 7 by any conventional means. It will be seen that when the cup 11 is moved toward the casing 3, the spring 10 is compressed and the button 8 is made to impinge on the transmitter diaphragm 5, thereby preventing its vibration and hence preventing any sound from being transmitted through it. The spring 10 normally holds the button 8 in a disengaged position. It will also be evident that thus damping the transmitter diaphragm will not interfere with the operativeness of the receiver.

What I claim and mean to secure by Letters Patent, is:

In combination with a transmitter diaphragm, a casing, a rod piercing the casing, said rod having a button on its inner end, a washer positioned on said rod externally to said casing, a spring positioned on said rod externally to said washer, a cup secured at the end of said rod and partially enveloping said spring, the button on said rod being positioned adjacent said transmitter diaphragm.

In testimony whereof I affix my signature.

PHILIP J. WERBER.
